HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC-CONTROLLING APPARATUS

Application filed July 10, 1928. Serial No. 291,505.

My invention relates to railway traffic controlling apparatus, and particularly to apparatus of the type comprising a plurality of sections of railway track separated by insulated joints and each provided with governing means controlled by currents separately supplied to the several sections.

One object of my present invention is to prevent improper operation of the governing means for one section by current from an adjacent section.

I will describe three forms of railway traffic controlling apparatus embodying my invention, and will then point out the novel features thereof in claims.

In the accompanying drawing, Fig. 1 is a diagrammatic view illustrating one form of railway traffic controlling apparatus embodying my invention. Fig. 2 is a diagrammatic view showing a modified form of the apparatus illustrated in Fig. 1, and also embodying my invention. Fig. 3 is a diagrammatic view showing still another form of the apparatus illustrated in Fig. 1 and also embodying my invention.

Similar reference characters refer to similar parts in each of the three views.

Referring first to Fig. 1, the reference characters 1 and 1^a designate the track rails of a stretch of railway track over which traffic normally moves in the direction indicated by the arrow. These track rails are divided into a plurality of successive track sections A—B, B—C, etc., by means of insulated joints, designated by the reference characters 2 and 3 with exponents corresponding to the location, and inserted in the track rails 1 and 1^a, respectively. Each such track section is provided with a source of unidirectional current here shown as a battery designated by the reference character D with an appropriate exponent. Each battery D is connected in series with a resistance 4 across the rails of the corresponding section at the exit end of the section, and the batteries are arranged in such manner that the rails of adjacent sections have opposite polarities. Each track section is further provided with a track relay designated by the reference character R with a suitable distinguishing

exponent, and connected across the rails adjacent the entrance end of the section.

Located adjacent the entrance end of each section, and controlled by the relay R for the section, is a roadside signal designated by the reference character S with an exponent corresponding to the location. As here shown, these signals are of the type known as "light signals" each comprising two electric lamps 8 and 9, indicating "stop" and "proceed" respectively when lighted. Each signal S is supplied with energy from a battery designated by the reference character E with a suitable exponent, and the supply of this energy is controlled by a contact 5 of the associated relay R. Referring particularly to signal S^B, when relay R^B is energized, lamp 9 is lighted, and the circuit for this lamp passes from battery E^B, through wire 19, front contact 5—5^a of relay R^B, wire 18, lamp 9, and wires 17 and 16 back to battery E^B. When relay R^B is de-energized, lamp 8 is lighted, and the circuit for lamp 8 passes from battery E^B through wire 19, back contact 5—5^b of relay R^B, wire 21, lamp 8, and wires 20 and 16 back to battery E^B.

As shown in the drawing, section A—B and the section to the right of point C are unoccupied, but a train indicated diagrammatically at V, occupies section B—C. Relays R^A and R^C are therefore energized so that signals S^A and S^C indicate proceed, but relay R^B is de-energized because the axles of train V shunt the energy away from the relay, and signal S^B accordingly indicate "stop."

With the apparatus thus far described, a dangerous condition might exist should one or both of the insulated joints 2, 3 break down at the entrance to an occupied section, thereby permitting current from the adjacent section to energize the track relay for such occupied section. For example, I will assume that joint 2^B breaks down. Under these conditions current might flow from battery D^B through wire 22, rail 1 of section A—B, rail 1 of section B—C, wires 23 and 24, winding of relay R^B, wires 25, 26, and 27 to rail 1^a of section B—C, thence through the ground around insulated joint 3^B to rail 1^a.

of section A—B, and so through wire 28, resistance 4, and wire 29 back to battery D^B. The resistance of the ground between rail 1^a of section B—C and rail 1^a of section A—B might, under some conditions, be so low that the current supplied to relay R^B would be of sufficient magnitude to pick up the relay. In similar manner should insulated joint 3^B break down, current might flow from battery D^B through wire 22, rail 1 of section A—B, thence through the ground around insulated joint 2^B to rail 1 of section B—C, through wires 23 and 24, the winding of relay R^B, wires 25, 26, and 27, rail 1^a of section B—C to rail 1^a of section A—B through joint 3^B, and so through wire 28, resistance 4, and wire 29 back to battery D^B. Should insulated joints 2^B and 3^B both break down this condition would be exaggerated, for under these conditions, battery D^B would be connected directly across relay R^B through resistance 4. In any of these cases, therefore, it will be manifest that should an insulated joint break down and cause improper operation of relay R^B, signal S^B would indicate proceed even though a train occupies section B—C.

To prevent improper operation of the apparatus under the foregoing conditions, I connect in multiple with each relay R an asymmetric unit designated by the reference character 7 with an exponent corresponding to the location. Each asymmetric unit 7 is arranged in such manner that current of the polarity normally supplied to the track section to which each relay is connected will not flow through the unit, but current of the opposite polarity will flow through the unit. I also interpose between each asymmetric unit 7 and each track relay R another asymmetric unit 6, the units 6 being so disposed that a low resistance is offered to current of the polarity normally supplied to the relay, but a high resistance is offered to current of opposite polarity. It will be apparent, therefore, that with the units arranged in this manner, if an insulated joint breaks down between a forward section which is occupied and an adjacent rear section, so that the forward section is supplied with current from the rear section, the track relay for the forward section will not become energized by the current from the rear section, because the unit 7 associated with the relay will shunt such current away from the relay, and the unit 6 will offer a high resistance to the flow of current through the relay. Furthermore, with the units arranged in this manner, if one of the units fails, the failure will generally be readily detected, and in case it is not detected, the other unit will continue to protect the relay. For example, if unit 7 should become short circuited, or unit 6 open-circuited, the associated relay R will fail to become energized when the sec-

tion with which it is connected is unoccupied, and the failure will therefore be detected. If unit 7 should become open-circuited, unit 6 will still protect the relay, and if unit 6 should become short circuited unit 7 will protect the relay.

In the modification shown in Fig. 2, the apparatus includes in addition to the signaling circuits shown in Fig. 1, means for supplying at times alternating train controlling current to the rails of each track section, which current is furnished by a generator G connected with line wires 34 and 35. This train controlling current is applied to the track rails of each section by a transformer designated by the reference character T with an exponent corresponding to the location, the secondary of which transformer is connected in series with a reactance 11 between the track battery D and the resistance 4 for the section. The primary circuit for each transformer T is controlled by a front contact 10—10^a of the track relay R for the section next in advance, such primary circuit including the secondary 32 of a line transformer L, the primary 33 of which is connected across the line wires 34 and 35. It will be seen, therefore, that alternating train controlling current is applied to the track rails of each section except the section in the rear of any occupied section. The alternating train controlling current thus supplied to the rails may be used to control train carried governing means in any suitable manner. In one form of train carried governing means suitable for cooperation with the trackway apparatus here shown, a proceed indication is received on board the train when train controlling current is being supplied to the rails, but a stop indication is received on board the train when no train controlling current is being supplied to the rails.

Referring now particularly to the apparatus located at point B, the asymmetric units 6^B and 7^B are so disposed that current of the polarity normally supplied to the rails of section B—C by battery D^C is permitted to flow in the winding of relay R^B, but current of the opposite polarity in the rails of section B—C is prevented from flowing through the winding of relay R^B. I will now assume that either or both of insulated joints 2^B or 3^B break down. If section B—C is unoccupied when this occurs, so that relay R^B is energized, the rails of section B—C might then be supplied with both unidirectional current from battery D^B and alternating train controlling current from secondary 30 of transformer T^B. The polarity of the unidirectional current supplied to the rails of section B—C from battery D^B, however, is opposite to the polarity of the current supplied to the rails of section B—C from battery D^C, and it follows that this current cannot flow in the winding of relay R^B. The alternating train controlling cur-

rent, however, might flow in the winding of relay R^B during alternate half-cycles. In order to prevent this occurrence, I construct the parts in such manner that the maximum electromotive force of the transformer T^B is less than the electromotive force of battery D^B . With this arrangement, the resultant current supplied from section A—B to relay R^B always has the same polarity, although the current contains an alternating component. This resultant current is prevented from flowing through relay R^B , and the relay therefore opens. The circuit for primary 31 of transformer T^B is then open at contact 10—10^a, and under these conditions, the rails of section A—B are supplied with unidirectional current only. As a result, the only current which might now be supplied to the rails of section B—C from section A—B due to a broken down insulated joint will be unidirectional current from battery D^B , and the relay R^B will therefore be protected from improper operation by asymmetric units 6^B and 7^B . It will be manifest, therefore, that with the apparatus arranged in the manner shown in Fig. 2, it is impossible for relay R^B to become improperly energized by stray currents supplied to the relay due to a broken down insulated joint, and so it is impossible for a train to receive a proceed indication when a stop indicaton should be received.

Referring now to Fig. 3, I have shown associated with each track section a line relay which is designated by the reference character F with an exponent corresponding to the location, and which is supplied with current from a battery E over a back contact 36 of the relay R for the section whenever the relay R for the section is de-energized. Referring particularly to section B—C, when line relay F^C is energized and when track relay R^C is de-energized train controlling current is supplied to the primary 31 of transformer T^C , over a circuit which passes from secondary 32 of the line transformer L^C , through wire 47, front contact 12 of relay F^C , wires 40 and 41, contact 14, wire 42, front contact 10—10^a of relay R^C , wire 44, primary 31 of transformer T^C , and wires 45 and 46 back to secondary 32 of transformer L^C . When line relay F^C is energized and when track relay R^C is de-energized, train controlling current is then supplied to the primary 31 of transformer T^C over another circuit which passes from secondary 32 of transformer L^C , through wire 47, front contact 12 of relay F^C , wire 40, contact 13, wire 43, back contact 10—10^b of relay R^C , wire 44, primary 31 of transformer T^C , and wires 45 and 46 back to secondary 32 of transformer L^C .

The train controlling current supplied to the track rails by transformer T may be periodically varied by means of cams O^1 and O^2 which are driven at constant speed by means of a motor M supplied with current

from secondary 32 of transformer L over front contact 12 of relay F when relay F is energized. The cam O^2 operates the contact 14 for supplying high speed or "proceed" code to the rails of the section, and the cam O^1 controls the contact 13 for supplying low speed or "stop" code to the rails of the section. High speed code can only be supplied when relays F and R are both energized, and low speed code can only be supplied when relay F is energized and relay R is de-energized. The trackway apparatus here shown is suitable for cooperation with train carried governing means which are selectively responsive in any suitable manner to the variations in the train controlling current. It is understood that although I have shown means for periodically varying the train governing current at two rates, my invention is not limited to this number.

With the apparatus constructed in the foregoing manner, a train entering section A—B while section B—C is occupied normally receives a slow speed or "stop" code. If an insulated joint should break down between sections A—B and B—C under these conditions so that track relay R^B becomes energized by energy supplied to section B—C from section A—B, the train in section A—B would receive a high speed or "proceed" code, while the train in section B—C would not receive any code because relay F^C would be de-energized. An undesirable condition might therefore exist. By associating asymmetric units 6^B and 7^B with relay R^B , unidirectional current supplied to section B—C from section A—B, due to a broken down insulated joint at point B, is prevented from flowing in the winding of relay R^B to energize the relay, and alternating current supplied to section B—C from section A—B under the same conditions, is also prevented from flowing in the winding of relay R^B during the alternate half cycles in which the current has the same polarity as the polarity of the unidirectional current supplied by section A—B. To prevent alternating current from section A—B from flowing in the relay winding during the remaining half cycles, I construct the secondary 30 of transformer T^B in such manner that the maximum electromotive force at its terminals at any instant is less than the electromotive force of battery D^B . With the parts arranged in this manner, the current which might be supplied to section B—C from section A—B always flows in such a direction that asymmetric units 6^B and 7^B will prevent this current from energizing the relay R^B , and a dangerous condition cannot therefore exist even though an insulated joint does break down.

Although I have herein shown and described only three forms of railway traffic controlling apparatus embodying my invention it is understood that various changes

and modifications may be made therein within the scope of the appended claims, without departing from the spirit and scope of my invention.

Having thus described my invention, what I claim is:

1. In combination, a forward and a rear section of railway track separated by insulated joints in the track rails, a source of unidirectional current connected with the rails of the forward section, a track relay connected with the rails of the forward section, a source of unidirectional current connected with the rails of the rear section in such manner that the polarity of the rails of the rear section is opposite to the polarity of the rails of the forward section, means associated with said relay for preventing the relay from being energized by current from the rear section if an insulated joint breaks down but not interfering with the normal operation of the relay due to current normally supplied to the rails of the forward section, and traffic governing means controlled by said relay.

2. In combination, a forward and a rear section of railway track separated by insulated joints in the track rails, means for separately supplying the rails of said sections with unidirectional current in such manner that the polarity of the rails of the forward section is opposite to the polarity of the rails of the rear section, a track relay connected with the rails of the forward section, an asymmetric unit associated with said relay and arranged to permit current from the forward section to flow through the relay but to prevent current from the rear section from flowing through the relay if an insulated joint breaks down, and traffic governing means controlled by said relay.

3. In combination, a first and a second section of railway track separated by insulated joints in the track rails, means for separately supplying the rails of said sections with unidirectional current in such manner that the polarity of the rails of the first section is opposite to the polarity of the rails of the second section, a track relay connected with the rails of the first section, an asymmetric unit interposed between said relay and a track rail for preventing current from the second section from flowing through said relay if one of said insulated joints breaks down, and traffic governing means controlled by said relay.

4. In combination, a first and a second section of railway track separated by insulated joints in the track rails, means for separately supplying the rails of said sections with unidirectional current in such manner that the polarity of the rails of the first section is opposite to the polarity of the rails of the second section, a track relay connected with the rails of the first section, an asymmetric unit

connected in multiple with the relay for shunting the relay if current is supplied to the relay from the second section due to a broken down insulated joint, and traffic governing apparatus controlled by said relay.

5. In combination, a first and a second section of railway track separated by insulated joints in the track rails, means for separately supplying the rails of said sections with unidirectional current in such manner that the polarity of the rails of said first section is opposite to the polarity of the rails of said second section, a track relay connected across the rails of said first section, a first asymmetric unit connected in multiple with said relay to shunt current from said relay if current is supplied to said first section from said second section due to a broken down insulated joint, a second asymmetric unit interposed between said relay and said first asymmetric unit for preventing current from said second section from flowing through said relay if said first asymmetric unit fails, and traffic governing apparatus controlled by said relay.

6. In combination, a forward and a rear section of railway track separated by insulated joints in the track rails, a first source of unidirectional current, a first source of train controlling current connected in series with said first source of unidirectional current across the rails of said forward section, a second source of train controlling current, a second source of unidirectional current, means including said second source of train controlling current for connecting said second source of unidirectional current across the rails of said rear section in such manner that the polarity of the unidirectional current supplied to the rails of the rear section is opposite to the polarity of the unidirectional current supplied to the rails of the forward section, a track relay connected with the rails of the forward section, asymmetric units associated with said relay for preventing said relay from being energized by current from said second source of unidirectional current if an insulated joint breaks down, and traffic governing apparatus controlled by said relay.

7. In combination, a first and a second section of railway track separated by insulated joints in the track rails, a source of unidirectional current connected with the rails of the first section, a track relay connected with the rails of the first section, a source of unidirectional current connected with the rails of the second section in such manner that the polarity of the rails of the first section is opposite to the polarity of the rails of the second section, a transformer having its secondary interposed between said second source and a track rail, means controlled by a front contact of said relay for at times supplying the primary of said transformer with train con-

trolling current, asymmetric units associated with said relay for preventing the relay from being energized by current that might be supplied to the first section by the second source if an insulated joint broke down, and traffic governing means controlled by said relay.

8. In combination, a first and second adjacent sections of railway track separated by insulated joints in the track rails, a first source of unidirectional current connected with the rails of the first section, a track relay connected with the rails of the first section, a second source of unidirectional current connected with the rails of the second section and arranged in such manner that the rails of the first section are of opposite polarity from the rails of the second section, an asymmetric unit connected in multiple with said relay and arranged to offer a high resistance to the current supplied to the relay by the first source but to offer a low resistance to current that might be supplied to the relay by the second source if an insulated joint broke down, means for supplying the rails of the second section with train controlling current when said relay is energized but for disconnecting said supply when said relay is de-energized, and traffic governing means controlled by said relay.

9. In combination, a first and second adjacent sections of railway track separated by insulated joints in the track rails, a first source of unidirectional current connected with the rails of the first section, a second source of unidirectional current connected with the rails of the second section and arranged in such manner that the adjacent rails in the two sections have opposite polarities, a track relay connected with the rails of the first section, a first asymmetric unit interposed between said relay and a track rail and arranged to offer a low resistance to current supplied to the relay by the first source but a high resistance to current that might be supplied to the relay from the second source if an insulated joint broke down, an asymmetric unit connected in multiple with the first asymmetric unit and the relay and arranged to shunt current from the relay if the relay is supplied with current of a polarity opposite to that supplied by the first source, means controlled by the relay for at times supplying the second section with train controlling current, and traffic governing means controlled by said relay.

10. In combination, a first and a second section of railway track separated by insulated joints in the track rails, a source of unidirectional current connected with the rails of the first section, a first relay connected with the rails of the first section, a second relay connected with the rails of the second section, a transformer, a second source of unidirectional current connected across the

rails of the second section in series with the secondary of said transformer and arranged in such manner that the polarity of the rails of the first section is opposite to the polarity of the rails of the second section, a line relay controlled by a back contact of said second relay, means controlled by the line relay for at times supplying the primary of said transformer with train controlling current which is periodically varied at one frequency when the first relay is energized but which is periodically varied at another frequency when the first relay is de-energized, asymmetric units associated with said first relay for preventing said first relay from being energized by current from the second section if an insulated joint breaks down when the first section is occupied, and traffic governing means controlled by said first relay.

In testimony whereof I affix my signature.

HOWARD A. THOMPSON.
